UNITED STATES PATENT OFFICE.

EUCLID I. LA CHAPELLE, OF BROCKTON, MASSACHUSETTS.

METHOD OF MAKING BOX TOES.

Application filed February 10, 1925. Serial No. 8,150.

The present invention relates to leather box-toes.

In making leather box-toes it is customary first to skive the front and back edges 5 of the box-toe blank to a blunt edge, and then to reduce the blunt front and back edges to a feather edge by a scouring operation. The scouring of the back edge may be performed roughly as this edge is drawn 10 in the lasting operation beneath the tread surface of the shoe. The front edge, however, must be scoured with great care to insure uniformity throughout the feather as any irregularity shows through the upper 15 in the finished shoe. Leather box-toes present difficulties in lasting owing to the necessity of performing the pulling-over operation under considerable tension in order to stretch the skived and scoured front edge 20 of the box-toe and set it firmly on the top and sides of the last. Moreover, leather box-toes, although highly desirable in turn shoes, are not used therein to any extent because the skived and scoured front edge 25 rolls over towards the toe-end of the shoe when the shoe is turned right side out. This rolling of the front edge of the toe box necessitates a tedious operation at the time 30 of relasting in order to unroll the toe box between the upper and lining. It has been proposed to stitch the skived and scoured front edge of the toe box to the turn shoe upper and lining to prevent this rolling 35 of the front edge of the toe box. This construction, however, created a condition worse than before owing to the shrinking of the lining subsequent to its becoming wet during the tempering of the attached toe box preparatory to the lasting operation.

40 The disadvantages of the customary leather box-toes may be enumerated as follows:

45 1. They are expensive to manufacture owing to the care required to scour properly the front edge of the box-toe blank.

2. They require extra tension in the pulling over operation in order that the skived and scoured front edge of the toe box may be properly lasted, and

50 3. They cannot be used to advantage in turn shoes.

The object of the present invention is to produce a leather box-toe which will be economical to manufacture, which will obviate the necessity of an extra tension in

the pulling-over operation, and which will be suitable for use in turn shoes.

To the accomplishment of this object, and such others as may hereinafter appear, the features of the invention relate to certain 60 combinations, arrangements of parts, and methods of manufacture, hereinafter described and then set forth broadly and in detail in the appended claims which possess advantages readily apparent to those skilled 65 in the art.

The various features of the present invention will be best understood from an inspection of the accompanying drawings illustrating the best forms of the invention 70 at present devised, in which,

Figure 1 is a plan of a box-toe blank at a preliminary stage of its manufacture;

Fig. 2 is a sectional elevation on the line 75 2—2, Fig. 1;

Fig. 3 is a detail in sectional elevation of the tempering box;

Fig. 4 is a detail showing the rolls for 80 rolling the skived front edge of the blank down to a feather edge, and

Fig. 5 is a central sectional elevation, similar to the section of Fig. 2, showing the finished box-toe.

Referring to Fig. 1, the box-toe blank 1 is skived along its back edge 2 and its front 85 edge 3 in the usual manner. Also, in the usual manner, the skived back edge 2 is reduced to a feather edge in a scouring machine. Instead of scouring the front edge 3 to a feather edge, an operation which must be carefully performed to prevent irregularities showing through the upper in the finished shoe, I treat the blunt front edge 4 (Fig. 2) in order to make it more rigid than the rest of the blank. This treatment of 90

the front edge may consist in applying glue, size or other stiffening material to the front edge. With the front edge treated to render it more rigid than the rest of the blank I find that the box-toe 1 may be used in turn 100 shoes with no liability of the front edge 3 rolling backward during the turning operation. I have determined that if the front edge is tempered and then dried prior to the tempering of the whole box-toe preparatory to the lasting operation the front edge will be rendered more rigid than the rest of the blank. This, I take it, is due to the property leather possesses of stiffening additionally with successive wettings. 105

In order to conveniently temper the front edge faces of a large number of blanks I provide a box 5 (Fig. 3) having water therein to a depth sufficient to temper the front edges 5 of the blanks only. The box 5 is provided with a series of transverse rods 6 against which the box-toe blanks rest with the front edges thereof immersed in the water.

In order to reduce the blunt end 4 of the 10 tempered front face 3 to a feather edge I pass the blunt end 4 between a pair of rolls 7 and 8 which are shaped to squeeze the face 3 into a feather edge. By rolling the tempered face 3 into a feather edge I compress 15 or compact the fibers of the face 3, as seen at 9 (Fig. 5), thus rendering the face 3 more rigid than the rest of the blank.

The face 3 may be squeezed, forced, or compacted into a feather edge by a pounding, 20 ironing or pressing operation but owing to convenience and rapidity of operation I prefer to pass the front edge 3 between the pressure rolls 7 and 8.

By my improved constructions and methods 25 of manufacture I am able to finish the front edge of the box-toe without the expensive front edge scouring operation. I am also able to use my improved box-toe in turn shoes as it is impossible for the stiffened 30 front edge to roll in the turning operation. Owing to compacted front edge the box-toe fits the top and side faces of the last without any unusual tension in the pulling-over operation.

35 What is claimed as new, is:

1. That improvement in the art of making box-toes which consists in reducing the front and back edges of a box-toe blank to a feather edge and treating the front edge 40 of the blank to render it more rigid than the rest of the blank.

2. That improvement in the art of making box-toes which consists in skiving the front and back edges of a box-toe blank, 45 scouring the skived back edges of the blank to a feather edge, and treating the front

edge of the blank to render it more rigid than the rest of the blank.

3. That improvement in the art of making box-toes which consists in skiving the 50 front and back edges of a box-toe blank, scouring the back edge of the blank to a feather edge, and compressing the front edge of the blank to a feather edge.

4. That improvement in the art of making box-toes which consists in skiving the front and back edges of a box-toe blank, 55 scouring the skived back edge of the blank to a feather edge, tempering the skived front edge of the blank, and compressing the tempered front edge of the blank to a feather edge.

5. That improvement in the art of making box-toes which consists in skiving the front and back edges of a box-toe blank, 60 scouring the back edge of the blank to a feather edge, and additionally stiffening the front edge only of the blank.

6. That improvement in the art of making box-toes which consists in skiving the 70 front and back edges of a box-toe blank, scouring the back edge of the blank to a feather edge, tempering the front edge only of the blank, and rolling under pressure the front edge only of the blank to a feather 75 edge.

7. That improvement in the art of making box-toes which consists in skiving the front and back edges of a box-toe blank, and 80 treating the front edge of the blank to reduce it to a feather edge and render it more rigid than the rest of the blank.

8. That improvement in the art of making box-toes which consists in skiving the front and back edges of a box-toe blank, 85 scouring the skived back edge of the blank, and tempering the skived front edge only of the blank.

In testimony whereof I have signed my name to this specification.

EUCLID I. LA CHAPELLE.
